UNITED STATES PATENT OFFICE.

THEODORE GRAHAM GRIBBLE, OF MELTON CONSTABLE, ENGLAND.

TRAMWAY.

SPECIFICATION forming part of Letters Patent No. 760,983, dated May 24, 1904.

Application filed January 23, 1903. Serial No. 140,255. (No model.)

To all whom it may concern:

Be it known that I, THEODORE GRAHAM GRIBBLE, railway engineer, a subject of the King of Great Britain, and a resident of 1 5 Grove road, Melton Constable, in the county of Norfolk, England, have invented a certain new and useful Improvement in Tramways, (for which I have applied for a patent in Great Britain, No. 14,621, dated July 1, 1902,) of 10 which the following is a specification.

This invention relates to improvements in tramways, and has for its object a double-headed grooved rail which can be reversed and which upon reversal requires only that portion 15 of the pavement which is situated between the rails to be removed, thus leaving the outer pavement on each side of the way entirely undisturbed.

In order that this invention may be clearly 20 understood and more easily carried into practice, I have appended hereunto a sheet of drawings, upon which I have illustrated the nature of my said invention.

Figure 1 is a cross-section through the permanent way on the line of a tie-bolt. Fig. 2 25 is an enlarged cross-section of one of the rails shown in Fig. 1. Fig. 3 is an enlarged cross-section of one of the rails shown in Fig. 1, but taken through one of the chairs. Fig. 4 is an 30 elevation of one of the combination fish-plates and chairs looking from the inside of the way. Fig. 5 is an elevation of one of the intermediate chairs. Fig. 6 is a longitudinal sectional elevation of one of the bolt-heads and tubular 35 washers to same. Fig. 7 is a cross-section through Fig. 6.

In carrying this invention into effect the rail A is made reversible, with a double head a' a'' and two grooves a^3 a^4 , and is partly supported 40 by the chairs B and partly by the concrete C, the lower groove a^4 being filled in with concrete, so as to form a base of the whole available width of head, groove, and flange for the bearing of the rail between the chairs. 45 The chairs are formed of a pair of double-cranked angle-bars B B', which grip the rail A at top and bottom and which are made of sufficient length to form fish-plates where they occur at the joints a^5 of the rails. The lower 50 flanges b^2 of the chairs B are attached by bolts

F to the base-plate E and are provided with slotted holes b^3 for the bolt, so as to permit of the side B' of the chair after the nut f' has been removed being tilted over, as shown by dotted lines in Fig. 3, sufficiently to allow of 55 the rail A being removed without disturbing the other side, as hereinafter described.

In case the rolling loads should require it, the chairs may be placed upon metallic cross-ties, which would then take the base-plates E, 60 the flange of the side b' still being provided with the slotted bolt-hole for the purpose before described.

The bolts or fastenings H, which pass through the rails and secure the same to the 65 chairs, are provided with socket-washers, which are made in two halves J J' and secured together around the head of the bolt by the thimble K with the socket upon the outer side of the rails. The sockets J J' are made 70 of sufficient length to permit the end of the bolt or fastening H to be pushed sufficiently back when the bolts are removed and the chair B' has been tilted to permit of sufficient clearance for the removal and reversal of the rail 75 A without disturbing the pavement M on the outer side of the rail.

The tie-bolts N, which hold the track to gage in the usual manner, are provided at the ends with a right and left hand screw or gib 80 and cotter-coupling, which is coupled to the screw-bolts or fastenings H, the square heads of which are arranged on the outer side of the rail and furnished with socket-washers J J' of similar construction to those described to 85 the chairs.

Having now described my invention, what I claim as new, and desire to secure by Letters Patent, is—

1. The combination with the double-headed and grooved reversible tram-rail, of a chair in two sections for supporting the rail at the top and bottom and capable of permitting the rail to be removed without disturbing the pavement on the outer side of the rail and a concrete foundation to enter the lower groove of the tram-rail and support it across its entire face. 90

2. The combination with the double-headed and grooved reversible tram-rail, of a chair 95

in two sections for supporting the rail at the top and bottom and capable of permitting the rail to be removed without disturbing the pavement on the outer side of the rail, a concrete foundation to enter the lower groove of the rail and support it across its entire face and a fastening-bolt rotatably connected to one of the chair-sections and arranged to project through the bolt-apertures in the rail and 10 other chair-section.

3. The combination with a double-headed

and grooved reversible tram-rail and chair of a tubular or socketed washer in which the head of the bolt or fastening may be set back to allow of the rail being reversed substantially 15 as set forth.

In witness whereof I have hereunto set my hand in presence of two witnesses.

THEODORE GRAHAM GRIBBLE.
